UNITED STATES PATENT OFFICE.

WILLIAM HENRY NICHOLLS, OF BROOKLYN, NEW YORK.

MOLDING-MACHINE.

1,367,078.

Specification of Letters Patent.

Patented Feb. 1, 1921.

Application filed June 25, 1919. Serial No. 306,676.

To all whom it may concern:

Be it known that I, WILLIAM H. NICHOLLS, a citizen of the United States, and resident of the borough of Brooklyn, in the county of 5 Kings, city and State of New York, have invented certain new and useful Improvements in Molding-Machines, of which the following is a specification.

This invention relates to improvements in 10 apparatus for forming molds and has for its general object the provision of means for jolting or jarring the sand in a flask or flask member, squeezing or compressing the sand about the pattern, and drawing the pattern 15 from the mold or mold section, during a single operation of the apparatus.

Another object of the invention is to provide a molding machine having two relatively movable pressure heads for pressing 20 the sand about the pattern in the flask or flask member, and magnetic means carried by one of the pressure heads for automatically drawing the pattern when the pressure heads are separated.

25 Another important object of the invention is to provide a molding machine having a reciprocable flask supporting member, a normally stationary pressure head adapted to be swung laterally into and out of the path 30 of the flask supporting member, electromagnetic pattern drawing means carried by said pressure head adapted to be engaged by the pattern or pattern plate when the flask support is moved toward the pressure head, and 35 means for automatically making and breaking the circuit through the electromagnetic drawing means by the act of swinging the pressure head respectively into and out of register with the flask supporting member.

40 Another important object of the invention is to provide a molding machine having a combined pressure head and electromagnetic pattern drawing device, and means operated automatically by a part of the molding 45 machine for magnetizing and demagnetizing said combined pressure head and drawing device.

A further object of the invention is to provide a molding machine of the squeezer type 50 having a magnetic pressure head adapted to be engaged by the pattern plate and to hold and draw said plate from the mold upon separation of the pressure head and mold.

In the accompanying drawings—

55 Figure 1 is a side elevation of the apparatus partly in vertical section;

Fig. 2 a plan view of the apparatus, the normally stationary pressure head being shown swung laterally;

Fig. 3 a sectional view on an enlarged 60 scale taken through the circuit making and breaking means;

Fig. 4 a detail section on the line IV—IV of Fig. 6;

Fig. 5 an inverted plan of the valve disk; 65

Fig. 6 detail view partly in vertical section showing the valve for controlling the fluid pressure supply;

Fig. 7 an enlarged fragmentary section 70 showing the manner of packing the main piston;

Fig. 8 an inverted plan of the valve casting; and

Fig. 9 a plan view of the large squeezing 75 piston.

In the preferred embodiment of the invention illustrated in the drawings, the base 1 of the machine is formed at its upper end with a cylinder 2 having an open upper end.

A large hollow piston 3 having an open 80 upper end is adapted to reciprocate vertically in the cylinder 2 and is formed with a small cylinder 4. The cylinder 4 has an open upper end and a port 5 communicating with the interior of the hollow piston 3. A 85 small jolt piston 6 is adapted to reciprocate vertically in the cylinder 4 relatively to the main piston and said jolt piston is rigidly held to the under side of a pressure head or flask support 7 which normally rests on the 90 upper end of the main piston 3.

Brackets 8 and 8' extend horizontally from opposite sides of the cylinder 2 and a valve for controlling the supply of fluid pressure to the cylinders 2 and 4 is mounted 95 on the bracket 8. This controlling valve comprises a horizontally divided two-part casing 9 in which is mounted a rotatable valve disk 10 having two recesses 11 and 12 in the under side thereof and two pairs of 100 oppositely disposed lugs or projections 13 on the upper side thereof. The valve disk is adapted to be rotated by means of a handle 14 fixed on the upper end of a valve stem 15 the lower end of which is formed 105 with oppositely extending arms or projections 16 which engage between the pairs of lugs 13 on the valve disk. A spring 17 coiled about the valve stem serves to press the valve disk upon its seat. The valve casing 110 is provided with four openings 18, 19, 20 and 21 extending through the bottom

thereof. The opening 18 communicates with a flexible pipe 22^a connected with a pipe 22 which extends through the jolt piston 6 and communicates with the small cylinder 4. The opening 19 communicates with an air supply pipe 23 connected with a suitable source of compressed air. The opening 20 communicates with a pipe 24 leading to a recess 25 in the bottom of the cylinder 2. The opening 21 leads to the atmosphere and preferably has a pet cock 26 threaded therein to regulate the amount or rate of the exhaust. In order to prevent leakage past the large or squeezing piston 3 said piston is formed with a circumferential channel 27 in which is seated a split packing ring 28 preferably formed with a V-shaped channel 29 in its inner side. Air under pressure is admitted from the cylinder 2 into channel 27 at the inner side of the packing ring 28 through a plurality of passages 30.

An upright post 31 is rigidly held in a boss 32 formed on the bracket 8^a. A collar 33 is rigidly held to the post 31 adjacent the upper end of the post, and a laterally swinging arm 34 is pivotally held at one end to the post between said collar 33 and a collar 35 which is locked on the post by a nut 36. A vertically extending rod 37 is rigidly held at its upper end by nuts 38 to the free end of arm 34. The lower portion of rod 37 is adapted to engage in a slot or recess 39 formed in one side of a boss 40 on the bracket 8, and a nut 41 is threaded on the lower end of said rod and is adapted to engage under the boss 40 to resist upward pressure against the arm 34. The rod 37 and boss 40 serve also to limit the movement of arm 34 in one direction to arrest the upper pressure head at a point in register with the lower pressure head 7.

The upper pressure head or member comprises a rectangular block 42 rigidly held to the lower end of a screw 43 threaded through the arm 34 midway the ends of said arm, and a magnetic pressure head and pattern drawing device 44 of rectangular form rigidly held to the under side of the block 42. The magnetic pressure head 44 may be of any suitable construction. As shown, said head comprises a box-like cast-iron casing in which a plurality of electro-magnets 45 of the well-known "horse-shoe" type are mounted. A plurality of soft steel pole pieces 46 extend through the under side of the casing and are insulated therefrom by sleeves 47 of non-magnetic metal. The lower ends of the pole pieces are flush with the under face of the head 44 and the upper ends thereof engage against the ends of the magnet cores. Current is supplied to the magnet coils in the usual manner through line wires 48 and 49 which lead into the head 44 at one end and are connected at their

opposite ends with a suitable attachment plug 50 adapted to be engaged in a suitable wall socket. It will be obvious however that the wires 48 and 49 may be connected in various other ways with a suitable source of electrical current.

Means is provided operated by a movable part of the machine for automatically making and breaking the circuit through the coils of the magnets at the proper times during the operation of forming a mold. For this purpose, a circuit-making-and-breaking device or switch is interposed in the line wire 49 at a point intermediate the plug 50 and the head 44. This circuit-making-and-breaking device comprises a switch casing or box 51 in which is mounted a stationary terminal or contact 52 and a movable resilient terminal or contact 53, to each of which one branch of the wire 49 is connected. The spring metal contact plate 53 is normally out of engagement with the contact 52 and is adapted to be flexed and forced into engagement with said contact 52 by a fiber pin or actuating device 54. The fiber pin 54 slides in an aperture in boss 40 on bracket 8 and the outer end thereof is normally projected into the slot 39 in said boss by the resilient contact 53. The pin 54 is provided at its inner end with a collar 55 for limiting the outward movement thereof, and the outer end of said pin is adapted to be engaged by the rod 37 when said rod is swung into the slot 39.

The squeezing piston 3 is held against rotation in its cylinder 2 by means of a post 56 rigidly held to the cylinder head and extending upwardly through an aperture in the head of the hollow squeezing piston. The post 56 is formed with an enlarged head 57 which serves to prevent accidental forcing of the piston 3 out of the cylinder 2. The pressure head 7 and jolt piston 6 are held against rotation by a pin 58 depending from the head 7 and passing through an aperture is a spider 59. The spider 59 is formed integrally with cylinder 4 and piston 3 and serves also to brace the upper ends of said cylinder and piston without obstructing the escape of air from cylinder 4 through port 5 to the atmosphere through the open upper end of the hollow squeezing piston 3 during the jolting operation, as hereinafter described.

The mold frame 60 may be of any suitable construction. As shown, said frame comprises one section of the well-known interchangeable cope and drag, divided metallic flask having the usual lateral projections or handles 61 each of which is provided with a rigid upwardly extending pin 62. The usual bottom board 63 fits within the lower end of the mold frame or flask section 60. The pattern plate shown is of special construction but it will be obvious that various forms

of pattern plates may be employed, it being essential only that the pattern plate be formed wholly or in part of magnetizable material, or that the pattern or pattern plate 5 have secured thereto a magnetizable portion adapted to be engaged by the magnetic drawing means. As shown, the pattern plate or pattern supporting means comprises a lower plate 64 formed of aluminum or other 10 non-magnetizable metal and an upper plate 65 formed of soft steel or other magnetizable metal and rigidly secured by rivets or otherwise to the plate 64. The plate 64 is formed with the usual handle portions or 15 lugs 66 each of which is provided with the usual pair of apertures 67 adapted to receive the pins 62 on the handles 61 of the cope and drag members of the type of flask shown. The pattern or patterns 68 are 20 secured in the usual manner to the under side of the pattern plate.

To form a mold the flask and pattern are placed on the head 7 with the pattern plate resting on the head, and the flask is then 25 filled with sand. The handle 14 is then turned to permit air to flow from the source of supply through the pipe 23, port 19, valve cavity 11, port 18 and pipe sections 22^a and 22 into the small cylinder 4 beneath jolt piston 6. The piston 6 and head 7 will thus be elevated slightly until exhaust port 5 is uncovered, whereupon the piston and head will drop, this operation being repeated in rapid 30 succession as long as the controlling valve is held in the position just described. The sand in the mold frame is thus jarred and evenly compacted therein. The surplus sand is then struck off level with the top of the flask and the board 63 put in place. The 35 flask is then inverted or rolled over and placed upon head 7 with the bottom board 63 resting upon the head and the pattern plate resting upon the upper end of the flask, as shown in Fig. 1. The arm 34 is then 40 swung horizontally until rod 37 engages in slot 39 in the boss 40 formed on bracket 8. This movement of arm 34 not only carries pressure head 44 directly over the pressure head 7, but also automatically closes the 45 circuit through the coils of the magnets 45 since rod 37, as it passes into slot 39, forces pin 54 inwardly and thus presses resilient contact 53 against contact 52. The handle 14 is then 50 turned to connect ports 19 and 20 through valve cavity 12, and thus admit air from pipe 23 into the large cylinder 2 below squeezing piston 3 by way of pipe 24 and recess 25, whereupon piston 3 will be forced 55 upwardly, carrying with it the head 7 and the mold frame. As head 7 moves upwardly the pattern plate will abut against the under face of the magnetic pressure head 44 and the mold will be squeezed between the heads 7 and 44, forcing bottom board 63 upwardly 60 within the frame or flask section 60 and

firmly packing or ramming the sand about the patterns. Handle 14 is then turned to connect 20 and 21 through valve cavity 12 to exhaust the air from cylinder 2 through the pet cock 25 whereupon the piston 3, head 7, and the flask frame 60 with the formed mold, will move downwardly to their starting point. The pattern plate with the patterns attached thereto will, however, be held to the under face of the head 44 owing to 70 the lifting effect of the magnetic lines of force which pass between the pole pieces 46 of the electro-magnets 45 through the soft steel top plate or section 65 of the pattern plate. The pattern or patterns held to the 75 pattern plate are thus drawn from the mold automatically when the pressure heads 7 and 44 are separated at the completion of the squeezing operation. The operator then removes the flask. After the removal of the 80 flask the operator grasps the pattern plate by the handles 66 and pushes the same laterally, causing the arm 34 to swing horizontally to carry the head 44 out of alignment with head 7. This movement of arm 34 not 85 only carries head 44 out of the way of the operator to facilitate filling another flask, but also carries rod 37 out of slot 39 in the boss 40 on bracket 8, thus permitting contact 53 to force pin 54 outwardly and move 90 away from contact 52. The circuit through the coils of the magnets 45 is thus automatically broken, and the pattern plate is released and may be immediately turned over 95 and placed on head 7 and assembled with 100 another mold frame or flask section. It will thus be seen that means has been provided whereby molds may be jolted and squeezed, and the patterns drawn therefrom and assembled with another mold frame with great 105 rapidity.

What I claim is:

1. In a molding apparatus, the combination of relatively movable mold squeezing members, means for imparting a relative 110 movement between said members, and magnetic means on one of said members for holding a pattern against movement relatively to said member upon separation of the members.

2. In a molding apparatus, the combination of a magnetic mold-squeezing and pattern-drawing pressure head, a mold and pattern support; and means for moving said support toward and from said head to 120 squeeze a mold and automatically draw a pattern therefrom during a single movement of the support toward and from the head.

3. In a molding apparatus, the combination of an electro-magnetic mold-squeezing and pattern-drawing pressure head, means for magnetizing and de-magnetizing said head, a mold frame support, and means for moving said support toward and from the 125 130

- pressure head to squeeze a mold and draw a pattern therefrom during a single movement of the support toward and from the head.
4. In a molding apparatus, the combination of an electro-magnetic mold-squeezing and pattern-drawing pressure head, means for magnetizing and de-magnetizing said head, a mold frame support, and means for imparting a relative movement between said head and support toward and from each other to squeeze a mold and draw a pattern therefrom.
5. In a molding apparatus, the combination of an electro-magnetic mold-squeezing and pattern-drawing pressure head, means for magnetizing and de-magnetizing said head, a mold frame and pattern plate support movable toward and from said head, and a magnetizable pattern plate, movable with said support into engagement with said head.
6. In a molding apparatus, the combination of a vertically reciprocable mold frame support, a mold-squeezing and pattern-drawing pressure head, a laterally shiftable support for said head, and means for automatically magnetizing and de-magnetizing said head when the head is shifted respectively into and out of register with the reciprocable support.
7. In a molding apparatus, the combination of a vertically reciprocable mold frame support, a mold-squeezing and pattern-drawing pressure head, a laterally shiftable support for said head, means for automatically magnetizing and de-magnetizing said head when the head is shifted respectively into and out of register with the reciprocable support, and magnetizable pattern-holding means adapted to rest upon a mold frame carried by the support.
8. In a molding apparatus, the combination of magnetizable pattern-holding means, relatively reciprocable mold-squeezing members, and electromagnetic pattern-drawing means carried by one of said members.
9. In a molding apparatus, the combination of a mold-squeezing pressure head, electromagnetic pattern-drawing means carried by said head, a vertically reciprocable flask support, a flask mounted on the support, magnetizable pattern-holding means separably held to the flask, and means for imparting a preliminary jarring movement and a subsequent up and down squeezing and drawing movement to the flask support.
10. In a molding apparatus, the combination of an electro-magnetic mold-squeezing and pattern-drawing head, a flask support, a flask mounted on the support, magnetizable pattern-holding means separably held to the flask, and means for moving said support toward and from the head to squeeze a
- mold and draw a pattern therefrom during a single movement of the support toward and from the head.
11. In a molding apparatus, the combination of a reciprocable flask support, an electro-magnetic mold-squeezing and pattern-drawing head, a swinging support for said head whereby the head may be shifted into and out of alignment with the flask support, a flask mounted on the flask support, magnetizable pattern-holding means separably held to the flask, means controlled by the swinging movement of the head support for magnetizing and de-magnetizing the head when the head is shifted into and out of alignment with the flask support, and means for moving the flask support toward and from the head to squeeze a mold and draw a pattern therefrom during a single movement of the flask support toward and from the head.
12. In a molding apparatus, the combination of mold forming means, an electro-magnetic means controlled by the operation of the mold forming means for automatically drawing a pattern from a mold formed by the mold-forming means.
13. In a molding apparatus, the combination of a pattern, means for compacting sand about the pattern to form a mold, and electro-magnetic means controlled by the sand compacting means for automatically drawing the pattern from a formed mold and releasing the drawn pattern.
14. In a molding apparatus, the combination of a flask, a pattern plate supported by the flask and having a magnetizable portion, a mold-squeezing pressure head, an electromagnet carried by said head adapted to be engaged by the magnetizable portion of the pattern plate, and means for moving the flask toward and from the pressure head to squeeze sand in the flask and separate the flask and pattern plate during a single movement of the flask toward and from the head.
15. In a molding apparatus, the combination of a vertically reciprocable flask support, a flask, a mold-squeezing pressure head shiftable laterally into and out of the path of the flask support, an electro-magnet movable laterally with the pressure head, means controlled by the movement of the pressure head into and out of the path of the flask support for energizing and de-energizing said electro-magnet, and magnetizable means adapted to engage said electro-magnet when the flask support is moved upwardly toward the pressure head and having a pattern on its under side.

This specification signed this twenty-first day of June, A. D. 1919.

WILLIAM HENRY NICHOLLS.
